FIG. 3.

INVENTOR

L. D. VAN VALKENBURG.

Joseph J. O'Brien

ATTORNEY.

UNITED STATES PATENT OFFICE.

LEVI D. VAN VALKENBURG, OF HOLYOKE, MASSACHUSETTS.

LEVER PEN-RETAINER.

1,316,070.

Specification of Letters Patent. Patented Sept. 16, 1919.

Application filed July 30, 1918. Serial No. 247,458.

To all whom it may concern:

Be it known that I, LEVI D. VAN VALKENBURG, a citizen of the United States of America, and resident of Holyoke, in the county of Hampden and State of Massachusetts, have invented certain new and useful Improvements in Lever Pen-Retainers, of which the following is a full, clear, and exact description.

10 This invention relates to improvements in pen retainers, and one of its leading objects is to provide a retainer consisting of a lever and a spring thereof, a means for anchoring the spring to the pen cap in such a way that the lever will have a locking engagement against the pen cap.

Another object of the invention is to provide a pen retainer with a spring and lever connection wherein the spring provides the 20 trunnions for the lever; and the lever has locking engagement against the side of the pen cap or the clasp connected with the spring.

With the above and other objects in view, 25 the invention consists in certain new and useful construction, combinations and arrangement of parts clearly described in the following specification and fully illustrated in the accompanying drawings in which:

30 Figure 1 is a vertical sectional view of one form of the invention.

Fig. 2 is a transverse sectional view taken on line 2 of Fig. 1.

Fig. 3 is a detail rear elevation partly in 35 section of the spring and lever.

Fig. 4 is a side elevation partly broken away, of a modified form showing a pen cap clasp connected with the spring.

Referring to Figs. 1 and 2 particularly, 40 5 designates the pen cap tube, and 6 the end plug thereof which is snugly fitted in the rear end of the pen cap, and which provides the end wall 7 thereof. Pen cap tube 5 is formed with an opening 5^a and the plug 6 is formed with a longitudinal slot 6^a.

The retaining bar is in the form of a lever 8 which is provided or formed with lateral pivot fulcrum ears 9, the inner edge portions of which are rounded so that they 50 will have rocking engagement with the outer face of the pen cap tube 5. The fulcrum ears 9 are provided with openings 9^a which receive the trunnions 10 of the spring 11. The spring 11 has an arm 12 which engages 55 the upper end of the lever 8 and an arm or

leg 13 which extends through the opening 5^a and lies in the slot 6^a, whereby the ears 9 are maintained in rocking engagement with the outer face of the pen cap tube 5, and the lower end of the lever 8, which is provided with the ball point 14, is held by the spring tension of the spring leg 12, against the pocket of the user, or against the pen cap as the case may be.

By pushing the plug 6 endwise, the leg 13 of the spring may be withdrawn from inter-locking connection with the pen cap.

In Fig. 4, I show a construction wherein the spring 15 is provided with a leg 15^a which bears against the upper portion of 70 the lever 16, which lever is formed with the fulcrum ears 16^a and 16^b. The spring 15 is formed with a pen clasp 17 of the conventional construction, which clasp is adapted to grip a pen tube. The spring 15 is also 75 formed with trunnions 18 which extend through openings 18^a in the fulcrum ears 16^a and 16^b, so that the lower end of the lever will be held toward the pen cap.

It is seen that in the construction shown 80 in Figs. 1 and 2, the spring is anchored or retained within the pen cap tube, while in the construction shown in Fig. 4, the spring is held to the pen cap tube by a clasp, otherwise the principles of construction of the 85 two forms of the device are the same.

Having described my invention I claim:—

1. An article retainer consisting of a lever having lateral pivot ears providing a fulcrum, a spring having trunnions to engage 90 the ears and provided with a pair of legs extending from said trunnions, one of said legs engageable with the lever and the other of said legs insertible in an opening of a pen cap, and a plug insertible in a pen cap 95 for holding the said other leg anchor to said pen cap to permit the lever to have rocking engagement with the pen cap.

2. The combination with a pen cap of a lever having an offset portion providing a 100 fulcrum engagement on the lever, a spring having trunnions pivotally connected with the offset portion of the lever, the pen cap having an opening in its wall and the spring having a leg extending through said opening and having engagement with the lever so as to hold one end thereof toward the pen cap, and a plug in the pen cap for holding 105 the spring anchored therein.

3. In combination, a pen cap having an 110

opening through its wall, a spring having diverging legs one of which is inserted in the opening of said pen cap, a lever locked to the spring and having fulcrum engagement with the pen cap, and means for anchoring the spring against the inner side of the pen cap.

4. In combination, a pen cap, a lever having an offset portion providing a fulcrum engagement on the pen cap, a spring for forcing one end of the lever toward the pen cap, and means for anchoring the spring against the inner side of the pen cap to retain the lever in locking engagement with the pen cap, the spring having locking engagement with the lever.

5. A pen retainer consisting of a lever having fulcrum ears, a spring having trunnions pivotally engaged with said ears, said spring having means for connection with a pen cap, whereby said ears will have locking engagement

ment on the pen cap, and one end of the lever will be held toward the pen cap.

6. A pen cap consisting of a tube and a detachable plug providing an end wall therefor, said tube being formed with a transverse opening in its wall, and said plug being formed with a longitudinal recess in its sides, a spring extended through the opening and having one end portion thereof disposed in the recess and held against the inner side of the tube by said plug, said spring having an outer end portion provided with trunnions and a lever having ears pivotally connected with the trunnions and contacting engagement with the outside of the tube to provide fulcrum bearings on the tube for the lever, said spring engaging one end of the lever to hold the opposite end toward the tube.

LEVI D. VAN VALKENBURG.
